UNITED STATES PATENT OFFICE.

ELISHA BARKER MATHER, OF ROCHESTER, NEW YORK, ASSIGNOR TO MARTIN MINOT,
OF BROCKPORT, NEW YORK.

TWIST-DRILL.

989,379.

Specification of Letters Patent. Patented Apr. 11, 1911.

Application filed February 18, 1910. Serial No. 544,536.

To all whom it may concern:

Be it known that I, ELISHA B. MATHER, a citizen of the United States, and a resident of Rochester, in the county of Monroe and State of New York, have invented a new and Improved Twist-Drill, of which the following is a full, clear, and exact description.

Among the principal objects which the present invention has in view are: To provide a drill of the character specified wherein in the cutting area is reduced; to provide a drill of the character specified wherein is formed a central guide for the operation of the tool; to provide a construction for a drill of the character specified having a throated central opening for the passage of a guiding core formed in the metal by the drilling operation; and to provide a drill of the character specified of simple, efficient and economical construction.

One embodiment of the present invention is disclosed in the structure illustrated in the accompanying drawings, in which like characters of reference denote corresponding parts in all the views, and in which—

Figure 1 is a side view of a twist drill constructed in accordance with the present invention; Fig. 2 is a similar view, showing the drill in operation, the metal plate in conjunction therewith it is shown being illustrated as in section; Fig. 3 is a view of the drill constructed in accordance with this invention, a fragment of the cutting point being broken away to show in section the formation of the connecting web; and Fig. 4 is an end view of the tool shown in Figs. 1 to 3 inclusive, viewed from the cutting end.

Stated in language different from that used above, the purpose of the present invention is two-fold. By eliminating a certain section of the center of the drill, there is avoided the dead or non-rotated point, which in its operation retards the sinking of the drill, by reason of the fact that the point is forced through the metal only when the surrounding walls are, by the rotating ends, broken down. The core which the uncut centrally located metal thus forms, operates as a most efficient and desirable guide for cen-

tralizing the bit in its operation, thereby avoiding the drifting tendency in metal of unequal temper or composition.

As a result of the construction designed to serve the first mentioned purpose, the cutting edge of the tool is materially reduced, and, further, the elimination or reduction of the cutting edge is directed to that part of the edge offering the greatest resistance to the sinkage of the tool in the operation of drilling.

To form a tool in accordance with the present invention, the usual twist drill 5 is provided at the apex of the cone end with a slot 6. The slot 6 is formed to the width which practice dictates is the most desired for various qualities and kinds of metal. The slot 6 is extended upward into the body of the drill and follows the central and narrowed section of the connecting web thereof, and terminates at the upper end in an inclined surface 7. The surface 7 is formed to a single incline, its purpose being to extend to one side of the metal core raised from the bottom of the hole being bored, to deflect the same into a channel 8 on one side of the web connecting the cutting edges of the tool. For the purpose of description I will call the inclined surface a throat. A core 9, formed by the omission to cut the metal in line with the slot 6, is, by the throat 7, forced into the channel 8. In certain metals the core 9 will remain intact, being delivered by the inclined throat 7 into the channel of the drill into which the throat 7 leads. The core will lie in said channel assuming the spiral arrangement of the same.

In certain qualities of metal the core will break away at near the throat 7. In all qualities of metal the core, from its base to the throat 7, will remain intact. If the core breaks, as above stated, the broken particle is led out through the channels 8 and 10 in the usual manner for drills of this character.

It will be noticed by reference to the illustration shown in Fig. 1, that the cutting edge of the tool is materially reduced by the elimination of the apex of the cutting edge. The immediate result of this elimination is

that the metal cut by the said tool is diminished, and the sinking speed of the spool is proportionally increased.

Having thus described my invention, what I claim as new and desire to secure by Letters Patent is:—

A twist drill having a vertically disposed centrally located slot formed between the radial cutting edges of said drill, said slot 10 having an upper end wall extended across

the said slot to form a downwardly inclined surface to deflect laterally the core cut from the metal.

In testimony whereof I have signed this specification in the presence of two subscribing witnesses.

ELISHA BARKER MATHER.

Correction in Letters Patent No. 989,379.

It is hereby certified that the name of the assignee in Letters Patent No. 989,379, granted April 11, 1911, upon the application of Elisha Barker Mather, of Rochester, New York, for an improvement in "Twist-Drills," was erroneously written and printed "Martin Minot" whereas said name should have been written and printed *Morton Minot*, as shown by the records of assignment in this office; and that the proper corrections have been made in the files and records of the Patent Office and are hereby made in said Letters Patent.

Signed and sealed this 25th day of July, A. D., 1911.
